GOLF CLUB HEAD

John Reuter, Jr., Phoenix, Ariz., assignor to John Reuter, Jr., Inc., Phoenix, Ariz., a corporation of Arizona

Filed June 8, 1965, Ser. No. 85,627

Term of patent 7 years

(Cl. D34—5)

FIGURE 1 is a top plan view of a golf club head showing my new design;

FIGURE 2 is a front elevational view of the same;

FIGURE 3 is a bottom plan view of the same;

FIGURE 4 is a rear elevational view of the same;

FIGURE 5 is an end elevational view looking at the club head from the toe thereof;

FIGURE 6 is an end elevational view looking at the club head from the heel thereof; and lastly

FIGURE 7 is a cross-sectional view taken substantially from vantage line 7—7 in FIGURE 1.

The characteristic features of my design of golf club head reside in the appearance in plan view resulting from the combination of a substantially flat front face and a rounded rear face curved at its ends toward the front face, the radius of curvature of the rear face at the toe of the

putter head being shorter than at the middle thereof, with the heel truncated to leave a flat plane disposed substantially at a right angle to the substantially flat front face.

I claim:

The ornamental design for a golf club head, substantially as shown and described.
